(57) **CLAIM**

The ornamental design for a martial art training mat, as shown and described.

DESCRIPTION

FIG. 1 is a top plan view of a martial art training mat showing our new design;

FIG. 2 is a bottom plan view thereof;

FIG. 3 is a side elevational view thereof; and,

FIG. 4 is a perspective view thereof.

The shading shown in FIG. 2 represents a pattern that extends across the entire surface.
